BOBBY PIN OPENER

Clarence M. Welch, Tampa, Fla.

Application September 6, 1946, Serial No. 695,161

6 Claims. (Cl. 132—1)

1

The present invention relates to what is believed to be a novel and improved bobby pin opener.

It is a matter of common knowledge that opening jaws or limbs of so-called bobby pins is often an undesirable task. Various makeshift methods are followed in achieving the desired ends. For example, some users pry the jaws apart with finger nails and others resort to the equally undesirable method of opening the jaws with their teeth. Then, too, various other ways are resorted to, and since all such ways known to me are clumsy and objectionable, I have evolved and produced a simple, mechanical device which achieves the desired end with simplicity, expediency and convenience.

Briefly, the preferred embodiment of the invention comprises a finger ring having means thereon for opening bobby pins in a practical and reliable, as well as safe and sane manner.

More specifically, the invention comprises a finger ring provided, on top, with a pocket and an opening blade, together with an extension functioning as a finger guard and pin guide, the latter for effectively tracking and delivering the jaws of the pin into correct position for satisfactory opening purposes.

Other objects, features and advantages of the invention will become more readily apparent from the following description and the accompanying illustrative drawings.

In the drawings, wherein like numerals are employed to designate like parts throughout the views—

Figure 1 is an elevational view of a bobby pin opener constructed in accordance with my inventive ideas and showing the manner in which the opener is used.

Figure 2 is an enlarged side elevational view of the opener.

Figure 3 is a vertical and central longitudinal sectional view showing the details of construction and also showing, in dotted lines, the method of inserting and angling the bobby pin for jaw-spreading and opening purposes.

Figure 4 is a top plan view of the structure seen in the other figures.

Figure 5 is an end view, that is, an end elevation of Figures 2 and 4, respectively, observing the same in a direction from right to left.

Referring now to the drawings by distinguishing reference numerals, it will be seen that the opener, as a unitary structure, is denoted by the numeral 6, the same being of appropriate material and proportions. Said structure comprises

1 a finger ring 7 having a recessed boss 8 formed on its top portion. The recess or cavity of the boss defines a pocket 9 and the blade portion comprises an opening wedge 10, the effective edge thereof being thinned and sharpened to the desired degree. The extension 11 is twofold in purpose. It comprises a rectilinearly straight part formed integral with the ring and lined up with the pocket 9 and opening wedge or blade 10. It 15 is substantially V-shaped in cross-section, thus providing diverging wings or flanges 12 defining a central guide or runway 13. This part 11 serves as a shield to prevent injury to the finger and also functions as a runway and tracking guide for the bobby pin 14. This is a conventional type of pin and includes the usual straight and long stem 15 and shorter, corrugated limb 16.

The mode of use of the device will be clear by examining Figures 1 and 3. Figure 3 shows the 20 bobby pin in dotted lines and the manner in which it is applied and the jaws thereof wedged apart and spread to open position. The tip or jaw of the straight limb 15 rides along the guide channel 13 and into the pocket 9. The outwardly 25 flared jaw on the remaining limb 16 is directed against the edge of the wedge or blade 10 in an obvious manner. Thus, by properly guiding the pin into place and forcing the jaws into proper places, said jaws are spread apart. The ring on 30 the finger, as seen in Figure 1, and the jaws spread, and with the pin open, the user grasps said jaws and retains the same in open position as shown at the right in Figure 1. This step, therefore, prepares the pin for ready application to the tresses of one's hair.

It is believed that I have evolved and produced a simple and economical and practical ring-type bobby pin opener which is aptly fitted for the purposes intended and which achieves 35 desired results in a satisfactory and convenient manner. Those who use bobby pins at beauty parlors and at home will appreciate the real significance of the device under advisement. In such circumstances, it is evidently unnecessary 40 to dwell at greater length upon the commercial and equivalent aspects of the device.

In view of the foregoing description taken in conjunction with the accompanying drawings, it is believed that a clear understanding of the 45 construction, operation and advantages of the device will be quite apparent to those skilled in this art. A more detailed description is accordingly deemed unnecessary.

It is to be understood, however, that even 50 though I have herein shown and described a

preferred embodiment of my invention that the same is susceptible to certain changes fully comprehended by the spirit of the invention as herein described and within the scope of the appended claims.

I claim:

1. A bobby pin opener of the class described comprising a finger ring provided with means for accommodating and opening the jaws of a bobby pin, said means comprising a pocket for reception of the jaw on one limb and a wedge-shaped blade for coaction with the remaining jaw.

2. In a bobby pin opener of the class described comprising a finger ring provided with means for accommodating and opening the jaws of a bobby pin, said means comprising a pocket for reception of the jaw on one limb and a wedge-shaped blade for coaction with the remaining jaw, and further including a guide in alignment with the pocket and blade.

3. A bobby pin opener of the class described comprising a finger ring provided with a recessed boss defining a pocket and further defining a wedge-like jaw-opening blade.

4. A bobby pin opener of the class described comprising a finger ring provided with a recessed boss defining a pocket and further defining a wedge-like jaw-opening blade, and an elongated extension formed integral with said boss and adapted to overlie the finger of the user, said extension being V-shaped in cross-section and

constituting a protector shield and bobby pin guide.

5. A bobby pin opener of the class described comprising a finger ring provided with jaw receptive means for accommodating and opening the jaws of a bobby pin, and complemental means for initially receiving, guiding, and feeding the jaws toward and into said first named means.

6. A bobby pin opener of the class described comprising a finger ring provided with jaw receptive means for accommodating and opening the jaws of a bobby pin, and complemental means for initially receiving, guiding, and feeding the jaws toward and into said first named means, said second named means being in the form of an extension at right angles to the ring and, in practice, overlying a substantial portion of the finger of the wearer, whereby it has the additional function of shielding the wearer's finger against injury arising out of careless handling of the bobby pin.
